A. P. Greeley

Attorney

UNITED STATES PATENT OFFICE.

ALBERT HAYES, OF NEW YORK, N. Y., ASSIGNOR TO CARNOT DEVELOPMENT CORPORATION, A CORPORATION OF NEW YORK.

ROTARY PUMP.

1,238,139.

Specification of Letters Patent. Patented Aug. 28, 1917.

Application filed April 4, 1916, Serial No. 88,937. Renewed February 26, 1917. Serial No. 151,144.

To all whom it may concern:

Be it known that I, ALBERT HAYES, a citizen of the United States, residing at New York, in the county of New York, State of New York, have invented certain new and useful Improvements in Rotary Pumps, of which the following is a description, reference being had to the accompanying drawings, forming a part hereof.

10 My invention relates to rotary devices for pumping fluids and has for its object to provide a device for this purpose which is simple and inexpensive in construction, rapid and certain in operation, and effective 15 to raise a large quantity of liquid with slight power, will be capable of use in pumping fluids without regard to the solid matter they may contain, which will not have any valves or other parts liable to be cut 20 or worn away by grit or other abrasive matter and will run steadily and effectively.

With these and other objects hereinafter explained in view, my invention consists in the construction and combination of elements hereinafter explained and particularly pointed out in the claims.

Referring to the drawings,—

Figure 1 is a central vertical section of a pump embodying my invention, on line 30 1—1 of Fig. 2.

Fig. 2 is a top plan view of the same.

Fig. 3 is a horizontal section on line 3—3 of Fig. 2.

In the drawings 1 is a vertical shaft carried in a bearing in the end of a bracket 2 and having a pulley 3 on its upper end arranged to be driven by a belt 4 from a motor 5 here shown as an electric motor. The shaft 1 extends into and is secured in 40 a hub 6, from which radiate arms 7 to an annular rim 8. From the rim 8 extend downward bars 9 formed rigid with the rim. These bars 9 are inclined slightly inward toward their lower ends and at their 45 lower ends are provided with an annular rim 10 from which arms 11 extend inward, the inner ends of these arms 10 being connected by a central disk 12.

The hub 6, arms 7, rim 8, bars 9, rim 10, 50 arms 11 and disk 12 are either formed integral, as by casting, or are otherwise so joined

together as to form a rigid frame gradually tapering in diameter from its upper to its lower end. The hub 6 is of such length as to hold the shaft 1 firmly so that as the 55 shaft is rotated there will be no lateral movement of the frame.

Fitting on this frame is an inverted cone 13 open at its lower end. This inverted cone may be made of relatively thin sheet 60 metal or other material. If desired it may be made, where the device is to be used for pumping acid or other corrosive liquid, of non-metallic materials such as wood or glass or of metal coated with enamel or other 65 non-corrosive material and while it is desirable to have this inverted cone made as true as possible, any irregularity of shape will be corrected in fitting it onto the frame.

The inverted cone is preferably provided 70 at its upper end with a flange 14. Surrounding the upper end of this inverted cone is a chamber formed by a top 15, a bottom 16, having a central opening for the inverted cone and side walls 17, having at one point 75 an opening 18 from which extends discharge spout 19. The top 15 and bottom 16 of this chamber are rigidly supported from bracket 2 by straps 20 and 21.

In operation as the shaft 3 is rotated, 80 rotating with it the frame and the inverted cone, the lower end of the cone being immersed in the liquid to be raised, the liquid is caused by centrifugal force to climb the walls of the cone and is thrown out over 85 its upper end into the chamber surrounding it from which it flows through discharge spout 19.

The bars 9 aid in the operation by preventing slip of the liquid relative to the 90 inner surface of the cone.

The taper of the cone is preferably very slight, one inch to a foot being found in practice to be quite sufficient. The cone may be of any length desired. 95

Having thus described my invention, what I claim is:

1. In a rotary device for raising liquid, a shaft and means for rotating it and a rigid frame, carried by the shaft comprising a 100 series of vertical bars inclined inward at their lower ends, and a separately formed

inverted cone open at its lower end fitting the rigid frame.

2. In a rotary device for raising liquid, a shaft and means for rotating it, a rigid frame carried by the shaft comprising a hub, provided with radial arms, vertical bars carried by the arms inclined inward at

their lower ends and having their lower ends connected by radial arms, and a separately formed inverted cone open at its 19 lower end fitting the rigid frame.

This specification signed and witnessed this 29th day of March, A. D. 1916.

ALBERT HAYES.
